VOLATILE FUMIGANT PAD

Fred H. Mayer, Portland, Oreg.

Application June 26, 1956, Serial No. 593,877

4 Claims. (Cl. 299—24)

My invention relates to insecticide and deodorizing volatile fumigant pads of the same general description illustrated and described in my two Patents No. 2,054,434 dated September 15, 1936, and Patent No. 2,542,341 dated February 20, 1951, in which a cardboard supporting body is provided with cut out sections to form fingers and a coating of volatile fumigant material coated on said fingers.

The main object of this invention is to provide an improved method of preventing flaking off of the volatile fumigant coating material from the cardboard fingers of the support, during the breaking apart operation. With this new construction the coating can be made thinner thereby permitting said volatile fumigant coating material to present more surface to the air for evaporation thereby increasing the functional efficiency of the device.

Referring to the drawings, in which like characters of reference indicate corresponding parts throughout the several views—

Fig. I is a side elevation of fumigant pad embodying my invention.

Fig. II is a vertical section on line II—II of Fig. I.

Fig. III is a side elevation of the cardboard base of a fumigant pad embodying my invention.

Fig. IV is a traverse section on line IV—IV of Fig. I.

Fig. V is a cross sectional view taken on line V—V of Fig. I.

On the drawings, I indicates the body or cardboard base of my device. It includes a plurality of dependent fingers 2. The sections cut-out to form the fingers is represented by numeral 3. The cut out sections providing bumps or knobs 4 along the inside edge of the fingers 2. The vertical slots 5 perforating the upper part of the cardboard base are provided for easy separation of the cardboard and to provide a hanger for suspending each finger. Vertical perforating slots 6 are to provide an aperture that can be stretched open for easy suspension from a clothes hook.

In the manufacture of these fumigant pads the preferred method is to dip and repeatedly dip the bare cardboard base into a vat of melted naphthaline. A coating of predetermined thickness can be built up on the cardboard fingers by allowing the pad to cool down between dips. This dipping process produces a built up deposit of fumigant material 8 upon each of the fingers 2 and encases each finger on all sides with a coating of substantially uniform thickness. The coating material will conform somewhat in shape to the shape of the cardboard fingers 2 and finally the knob-like protuberance 4 will have a knob-like protuberance in the coating material forming a neck-like connection 7 between the fingers and openings 9 between the connections 7.

2

With this construction the coating material remains firmly attached to the cardboard fingers whether, or not, the frangible connection between the fingers breaks with a smooth surface, I have found that that portion 5 of the volatile coating material to be used as a means of reenforcing, with rivet-like effect, to prevent cleavage between the volatile fumigant coating material and the cardboard fingers, during the breaking apart operation, must be as close as possible to the point of cleavage between the fingers.

In view of the foregoing description taken in conjunction with the accompanying drawings it is deemed that a clear understanding of the invention will be apparent to those skilled in the art. Therefore a more detailed description 15 is accordingly thought unnecessary.

Having described the invention, what is claimed as new is:

1. A fumigant pad consisting of a cardboard support having a section cut out to form spaced dependant finger-like members, said finger-like members having one or more knob-like protuberances extending laterally into said cut out space and a coating of volatile fumigant material encasing said finger-like members on four sides and providing a frangible connection between the finger-like members.

2. A fumigant pad consisting of a supporting body having a section cut out to form spaced dependant finger-like members and a volatile fumigant material coated on four sides of said finger-like members, a frangible connection consisting of one or more spaced neck-like lateral protuberances formed in said volatile fumigant coating material, disposed between the finger-like members and extending to the fumigant coating material of the next finger-like member, providing the said frangible connection therebetween.

3. A fumigant pad consisting of a cardboard support having a section cut out to form spaced finger-like members and a volatile crystalline material coated on said finger-like members, said coating material providing a frangible connection between said finger-like members, said frangible connection being provided with weakening holes, the distance between said weakening holes being short enough to prevent loosening of the crystalline coating material from the said cardboard finger-like members, during the breaking apart operation.

4. A volatile fumigant pad consisting of a cardboard support having a section cut-out to form spaced dependent finger-like members, said finger-like members having a tooth-like projection extending laterally into said cut-out space, a coating of volatile fumigant material encasing said finger-like members, said coating material having a knob-like portion formed when coated on said tooth-like projection, the said knob-like portion of said coating material joining the coating material on the next finger-like member, providing a frangible connection therebetween.
